US00D556726S

(12) **United States Design Patent** (10) Patent No.: **US D556,726 S**
Dai (45) Date of Patent: ** Dec. 4, 2007

(54) **MOBILE PHONE**

(75) Inventor: **Jia Dai**, Shanghai (CN)

(73) Assignee: **Inventec Appliances Corp.**, Taipei (TW)

(**) Term: **14 Years**

(21) Appl. No.: **29/270,219**

(22) Filed: **Dec. 19, 2006**

(51) **LOC (8) Cl. 14-03**

(52) **U.S. Cl. D14/138; D14/346**

(58) **Field of Classification Search** D14/137, D14/138, 147, 218, 341-347; 455/90.3, 455/556.1, 556.2, 575.1, 575.3, 575.4; 379/433.01-433.13; 361/814; 348/14.02

See application file for complete search history.
